UNITED STATES PATENT OFFICE.

BENEDETTO TAMBURELLO, OF NEW YORK, N. Y.

DEMOUNTABLE RIM.

1,344,662.

Specification of Letters Patent. Patented June 29, 1920.

Application filed August 19, 1919. Serial No. 318,497.

To all whom it may concern:

Be it known that I, BENEDETTO TAMBURELLO, a citizen of the United States of America, residing at New York city, county 5 and State of New York, have invented certain new and useful Improvements in Demountable Rims, of which the following is a full, clear, and exact description.

This invention relates to improvements in 10 demountable rims, one of the objects being to provide an interchangeable rim, that is to say, a rim arranged to receive a straight side-tire or a clincher-tire. To accomplish this result, I provide a rim having detachable and reversible flanges to engage the beadings of tires. When in one position relative to each other the flanges will be 15 adapted to engage straight side-tires, and when in the other position they will be 20 adapted to engage clincher tires.

Other features of improvement will hereinafter appear. I will now proceed to describe my invention in detail, the novel features of which I will point out in the appended claim, reference being had to the 25 drawing, wherein,

Figure 1 is a sectional view of my improvement arranged for clincher tires;

Fig. 2 is a similar view of the device arranged for a straight side tire; and

Fig. 3 is a side view of a wheel equipped with my improved rim.

As herein arranged, my improved rim consists of a plurality of annular band-members 5 and 6 and a plurality of shiftable detachable curved flange members 7 and 8 together with fastening elements or screws 9. In practice the band members will be slipped on to a felly 10 of a wheel, 35 and the removable band 6 will be slipped over the band 5 and will rest upon projections 11 to maintain the band 6 clear of the band 5 to prevent rusting. The inner band 5 carries a concentric annular shelf portion 40 12 raised sufficiently from the band 5 to be flush with the band 6, that it to say, the top surfaces of said shelf and band will be flush. The shelf 12 and band 6 each carry a flange 45 13 and 14 respectively, to serve as a backing for the tire engaging flanges 7 and 8. When in use one tire-flange will rest upon

the shelf 12 and the other upon band 6. When the tire is pumped up the flanges or rings 7 and 8 will be forced against the adjacent flanges of their respective band members. 55

As the flanges 7 and 8 are removable from the band-members 5 and 6, they may be reversed. In other words, they can be placed upon the band members with the convex 60 portions outwardly or inwardly. When the flanges 7 and 8 are placed upon the bands with the convex portions outwardly they will be adapted to engage straight side tires. When placed upon the bands, with the convex portions inwardly, the flanges will be 65 adapted to engage clincher tires. The rim as a whole may be secured to the wheel by the usual wedges 10^a and bolts 10^b. The rim can be removed from a wheel after the 70 wedges 10^a have been removed, this fastening means being well known. It will be evident from the foregoing that my improved device is well adapted for use in connection with straight side or clincher tires, by 75 merely reversing the position of the tire engaging flanges. After the rim, as a whole, has been removed from a wheel the band members can be taken apart, after the screws 9 have been removed. The outer tire engaging flange will of course slip off when band 5 is removed. 80

Having described my invention what I claim is:

1. A tire supporting assembly consisting 85 of a band to engage a wheel, a raised annular shelf carried by the said band concentric therewith, upstanding projections carried by said band a second band removably supported by the first named band and resting upon said projections, said second band being flush with said raised shelf, a tire engaging flange removably supported by said shelf, a second tire engaging flange carried by the removable band, and an upstanding 90 flange carried by each band-member to engage the adjacent tire engaging flange. 95

2. A tire supporting assembly consisting 100 of a band to engage a wheel, a raised annular shelf carried by the said band concentric therewith, upstanding projections carried by said band, a second band removably sup-

ported by the first named band, and resting upon said projection, said second band being flush with said raised shelf, a tire engaging flange removably supported by said shelf, 5 a second tire engaging flange carried by the removable band, an upstanding flange carried by each band member to engage the adjacent tire engaging flange, and screws to

secure one band to the other, said screws passing through some of said projections. 10

Signed at New York city, N. Y., this 15 day of August, 1919.

BENEDETTO TAMBURELLO.
